CLAIM

The ornamental design for a therapeutic wrap, as shown and described.

DESCRIPTION

FIG. 1 is a front elevational view of a therapeutic wrap showing our new design;

FIG. 2 is a rear elevational view thereof;

FIG. 3 is an enlarged left side elevational view thereof;

FIG. 4 is an enlarged right side elevational view thereof;

FIG. 5 is a top plan view thereof; and,

FIG. 6 is a bottom plan view thereof.

In the figures, the even-length dashed or broken lines are used to represent unclaimed subject matter and thus form no part of the claimed design.
